DISPLAY FORM

Felix Schlag and Albert Fuggiti, Chicago, Ill.

Application May 25, 1931, Serial No. 539,965

2 Claims. (Cl. 223—18.3)

This invention relates to display forms and more particularly to a form for use in displaying gloves for dress-wear which is shaped like a human hand.

5 The forms in present use have been made of solid material such as plaster of Paris and the like, which is brittle and easily broken.

Another objection to the present type of forms is that the fingers are rigid. This requires careful handling of the glove when the same is fit onto the form, to prevent the breaking off of the fingers.

In order to overcome these objections we propose to make a form of resilient material.

15 Another object of the invention is to provide a resilient form having a supporting plate which has attached thereto a plurality of spring members extending therefrom into the fingers of the form in close proximity to the tips thereof, 20 and which will serve to return the fingers to their normal shape after fitting a glove on the form.

Another object is to provide a form wherein the spring members are placed in the mold before pouring of the material for the form, thereby serving as reinforcing members.

In order that the invention may be readily understood and the manner of the utilization made clear, the embodiment of the same is set forth in the accompanying drawing and in the following detailed description predicated thereon. Obviously, the invention is susceptible of embodiment in other and varied forms without sacrifice of material advantages, wherefore the drawing and description are to be taken in an illustrative and not an unnecessarily limiting sense.

In the drawing:

Figure 1 is an elevational view of a display form in which a hand is illustrated, with parts broken away and shown in section.

Figure 2 is a perspective view of the same, and

Figure 3 is a detail section of a modified form. Referring more particularly to the drawing, 45 1 indicates a base to which a supporting plate 2 of a display form 3 is attached by the screws 4.

The form 3 is shaped similarly to a hand and 50 includes fingers 5 and a wrist 6 which rests upon the plate 2.

Inserted into openings 7 in the plate 2 are the spring reinforcing rods 8, which extend thru the wrist 6 and into the fingers 5 in close 55 proximity to the tips 9.

The hand in the present instance is made of a resilient material such as india-rubber, thereby providing flexible fingers which may be bent relative to each other to facilitate the insertion thereof into the fingers of a glove, the spring rods 8 serving to return the fingers 5 to their normal position.

In Figure 3 is shown a modified form in which the plate 2' rests in a recess 10 in the base 1:

Arranged in the resilient form 3' are coil springs 8' which are inserted into the openings 7' in the plate 2' and secured thereto by solder.

From the foregoing it will be seen that we have provided a simple and efficient device, which may also be utilized as a support for displaying a shoe or the like. In this case the shoe is placed in the hand of the form 3, with the fingers 5 bent backwardly, the spring members then serving to return the fingers 5 towards their normal position, thereby gripping 75 and holding the shoe in place.

Having thus described the invention, what we claim as new and desire to protect by Letters Patent is:—

1. In a device of the class described, in combination, including a base having a recess in the upper face thereof, a plate mounted in said recess, a solid rubber hand mounted on said plate, having resilient reinforcing members, said resilient members being arranged in the fingers 85 of said hand and extending beyond the wrist portion of said hand, said plate having a plurality of openings therein adapted to receive the extending portions of said resilient members. 90

2. In a device of the class described, in combination, including a base having a recess in the upper face thereof, a perforated plate mounted in said recess, a solid rubber hand mounted on said plate and having resilient reinforcing rods 95 moulded in the fingers thereof, one of the ends of said members terminating in close proximity to the tips of said fingers, the other ends extending beyond the base of said hand and into and fixed to said plate. 100
